UNITED STATES PATENT OFFICE.

DAVID E. HOPPER, OF PATERSON, NEW JERSEY.

GAS-COCK.

No. 893,847.

Specification of Letters Patent.

Patented July 21, 1908.

Application filed January 9, 1908. Serial No. 409,989.

To all whom it may concern:

Be it known that I, DAVID E. HOPPER, a citizen of the United States, residing in Paterson, Passaic county, New Jersey, have invented a certain new and useful Improvement in Gas-Cocks; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has for its object to provide a gas-cock which shall combine with its key a novel means for locking the same when closed, so as to guard against accidental or unconscious reverse turning of the key after the same has been turned sufficiently to extinguish the flame.

My invention will be found fully illustrated in the accompanying drawing, wherein,

Figure 1 is a side view of one form of the improved gas-cock, the key being in the closed position; Fig. 2 is a longitudinal horizontal sectional view, the key being in the open position; Fig. 3 is an underneath view, partly in section; and Fig. 4 is an underneath view, the key being open and shown in section.

In the drawings, referring first to Figs. 1-4, *a* is the casing of the improved gas-cock, the same being of ordinary construction, except as hereinafter indicated, and having the usual attachment nipples *b* and *c*.

d is the key, the same comprising the usual conical plug *e* and the key proper or handle *f*; in the plug is formed the bore *g* which, according to the position of the key, stands aligned with the bore *h* of the casing or out of registry therewith.

The plug *e* projects slightly from the casing, as shown best in Fig. 1, and in this projecting portion is formed a vertical notch *i*. At one side of the key and on the lower side of the casing *a* is cast a box *j* opening outwardly and also toward the key and in this box, on a pivot *k* extending parallel with the axis of the key, is pivoted a pawl *l* which has an inwardly projecting tooth *m* at the end thereof which is the nearer to the key and an outwardly projecting knob *n* at its other end.

The pawl is held with its tooth normally bearing against the side of the key by means of a spiral spring *n'* introduced into the box and interposed between the outer end of the

pawl and the opposed wall of the box. The pawl *l* lies in a horizontal plane coinciding with that of a semi-circular downwardly projecting shoulder *o* on the casing, making of the whole structure a more compact and metal-saving one than would otherwise be produced, and when its tooth is engaged with the notch in the key in the closed position of the latter, as shown in Figs. 1 and 3, it is sufficiently close to the adjoining end of said shoulder that the latter will serve as an abutment with which said pawl may contact to prevent undue strain being brought on the pivot of the pawl in further attempt to turn the key after it is once locked by the pawl.

It will be understood that upon turning the key from the open position (Figs. 2 and 4) to the closed position, (Figs. 1 and 3) the pawl snaps into the notch in the plug of the key and locks the key against movement in either direction, in this coöperating with the usual pin *p* which, when the pawl is engaged with the notch *i*, contacts with said shoulder. In order to turn the key to the open position, where it is limited by the pin *p* engaging the box *j*, the knob of the pawl is pressed upon until its tooth leaves the notch *i*, whereupon the key may be turned. It will be observed that the position of the pawl relatively to the handle of the key is such that it is practically impossible to open the key except by using both hands, thus increasing the element of safety.

I propose to ream out the bore *g* at both ends thereof, giving the same the shape of a double cone. The object of this is to insure the gas remaining lighted until substantially the last instant before the key is locked in the closed position, thus preventing the operator from leaving the key, thinking it is entirely shut off and locked because the light may have been extinguished, with the result that a subsequent backward turning would cause leakage of the gas.

Having thus fully described my invention, what I claim as new and desire to secure by Letters Patent is:

In a gas cock, the combination, with the casing, of a rotary key, said casing having a semi-circular shoulder around the key forming at one end a stop for the key in its closed position and also having an integral box forming a stop for the key in its open position, and a spring-actuated pawl pivoted in said box on an axis parallel with that of the

2
key, said key having a notch adapted to be engaged by the pawl to lock the key in the closed position and the other end of said shoulder being disposed close to one end of the pawl and serving as an abutment therefor, substantially as described.

In testimony, that I claim the foregoing, I

have hereunto set my hand this twenty-eighth day of December, 1907.

DAVID E. HOPPER.
